UNITED STATES PATENT OFFICE

JOHN C. HOLZ AND GEORGE B. TROST, OF PECRIA, ILLINOIS

FUEL PUMP

Application filed December 13, 1928. Serial No. 325,717.

This invention relates to gasoline pumps and more particularly to a coin-controlled and automatically operating pump.

One of the objects of the invention is in the provision of a gasoline pump for curb service, the same being adapted to operate automatically upon the insertion of a coin.

Another object is in the provision of a gasoline pump constructed for curb service, the same being arranged as to parts in a manner to obviate the necessity of an attendant and to permit the customer to insert a coin in the control mechanism with the result that the customer himself may withdraw a predetermined amount of gasoline for his vehicle.

Still another object is in the provision of a coin-controlled gasoline pump, the same being constructed in such manner that the insertion of a coin in the control mechanism and a subsequent operation by the customer results in the drawing off from the pump of a predetermined amount of gasoline, there being utilized a pressure operating mechanism automatically controlled for replenishing the pump.

A still further object lies in the provision of a gasoline pump devised for curb service, the same constructed in a manner to obviate the necessity of an attendant and including a coin-controlled mechanism for initiating the operation of the pump by the customer, there being included mechanism operating automatically upon a release of the control member for replenishing the pump, thereby placing same in operating condition for the following customer.

Other objects of the invention will appear in the following specification taken in connection with the annexed drawings, in which—

Fig. 1 is an elevational view, partially in section, showing the coin-controlled, automatically operating gasoline pump, the replenishing feature being adapted to be operated by means of pressure;

Fig. 2 is a cross-sectional view taken on the line 2—2 of Fig. 1;

Fig. 3 is a cross-sectional view taken on the line 3—3 of Fig. 1;

Fig. 4 is an elevational view, partially in section, the same disclosing electrically controlled mechanism for automatically replenishing the pump once the determined supply has been exhausted;

55

Fig. 5 is a diagrammatic view, showing the manner of installation of the pump and associated tanks and electrical control means for replenishing the pump;

Fig. 6 is a view similar to Fig. 5, with the exception that the automatic replenishing feature in this view is accomplished by means of pressure;

Fig. 7 is an enlarged detail showing a portion of the automatic mechanism for replenishing the pump, the same showing the valve controlling member in one position during lateral movement; and

Fig. 8 is a similar view, showing the operating lever in another position during its lateral movement.

Before referring to the drawings, it is thought well to set forth somewhat generally some of the results applicants desire to obtain with the present type of pump, which is not found in either the prior art or pump structures known to the public.

The matter of servicing motor vehicles has reached such a stage that practically every town or village has many of its corners and other locations dotted with so-called gasoline filling stations or gasoline service stations. Almost universally these stations have come to be practically standard in construction and in the character of service rendered. It is well known that the operator of a motor vehicle drives his car to a point adjacent the gasoline pump which may be either of the visible or other well known type. In practically every instance, the operator disposes the nozzle of the pump in the tank of the car, and thereafter, pumps a volume of gasoline into the tank of the vehicle, either by hand or by the operation of a lever which actuates a control pump of some sort which in turn projects the gasoline into the vehicle tank.

Applicants propose and disclose herein mechanism which is radically different from such well known pumps and one which

100

changes in its entirety the general feature of these service stations. The pump disclosed herein may be disposed in exactly the same position as those heretofore known, but it is adapted to be operated in an entirely different manner, in fact it is intended that the service of an attendant be obviated and that the overhead required in such a station be eliminated and this saving be given indirectly to the customer, due to the lowered cost of the gasoline. There is imposed, however, on the motor vehicle operator the requirement of taking off the cap of his gasoline tank, placing the pump nozzle therein and thereafter depositing a coin in the coin-controlled mechanism and finally operating a plunger which initiates a movement of the parts, permitting a predetermined amount of gasoline to flow into the tank. When this predetermined amount of gasoline has been projected into the motor vehicle tank, the operator thereupon releases the plunger and thereafter the pump mechanism operates automatically to replenish the pump and place same in normal condition for operation by a subsequent customer.

Referring specifically to the drawings, 10 designates a pump standard or framing, which supports at its upper end a visible gasoline container 11 to be watched by the customer during the withdrawal operation to see that he obtains his full amount of gasoline. This frame or standard 10 is disposed in any position desired, it being ordinarily supported upon a concrete base 12. A large remote gasoline tank 13 is sunk beneath the surface of the ground for the purpose of safety and an auxiliary tank 14 is operatively connected thereto, the latter being obviously full at all times and in a position from which gasoline may be readily withdrawn to the visible tank 11 by mechanism later to be described.

So far, it may be seen that the general construction of the pump is somewhat standard. Further, as respects the general features of the pump obviously not new, a hose member 15 is shown having a nozzle 16, all of ordinary construction. A valve member 17 controls the flow of gas from the visible pump 11 to the hose 15, means for operating which will be explained later.

A replenishing pipe 18 is disposed within the visible tank with its upper end well above the normal gasoline level therein, said pipe finally communicating with the gasoline tank 14 from which gasoline is forced in the replenishing process. A large overflow pipe 19 is disposed within the visible container, the same finally terminating in and communicating with the upper side of the large storage tank 13. It is obvious from the above that with such construction the level of gasoline within the visible container will always be on a line even with the upper edge

of the overflow pipe 19. The amount of gasoline carried within the visible container obviously may be varied, but it may be assumed that same is ordinarily five gallons.

Inasmuch as the description up to this point is general, both as to the pump disclosed in Fig. 1 and that disclosed in Fig. 4, the reference numerals have been repeated in these two figures, referring to similar parts, these features being conventional construction.

As stated before, there have been shown two pumps involving exactly the same principle and differing only in the manner of automatic operation, one operating by means of pressure and the other electrically.

Now, with respect to Fig. 1 and adjacent figures, relating thereto, disclosing the pressure-operated pump, an air pressure tank is shown, the same being of any conventional construction and normally applying pressure to the outlet pressure pipe 21. This pressure pipe 21 transmits pressure through a pipe designated 21 throughout up into the pump to a valve control member 22, the pipe 21 finally terminating in and communicating with the upper edge of the auxiliary tank 14.

Obviously, there is a pressure at all times on one side of the lever control valve 22 and when same is opened this pressure will be transmitted to the auxiliary tank 14, and therefore force gasoline up the pipe 18 and finally into the visible container, this operation continuing as long as the valve 22 is open.

Means for controlling the operation of this air valve 22 is as follows: A bracket 23 secured to the upper end of the pipe 18 disposed within the visible container supports in pivotal manner a conventional lever-controlled ball float mechanism 24. Movement of this ball float is transmitted to a vertical rod 25, the same being movable within an upright tube 26, secured as at 27 in a gasoline-tight manner to the bottom of the visible container. This tube merely surrounds the rod 25 to obviate the necessity of packing the rod 25 at the point that it would pass through the bottom of the container. Obviously, this tube 26 projects above the normal gasoline level within the visible pump. The lower end of the rod 25 has an adjustable connection 28 with the lever controlled air valve 22.

It is apparent from the above that movement of the ball float controls the movement of the lever controlled air valve, and thus the flow of gasoline into the visible pump.

Applicants, as stated above, propose to operate their pump automatically and by means of a coin-controlled mechanism, which has been disclosed generally as at 29, such a general showing thereof being considered

sufficient in view of the well known construction of such mechanism and the obvious possibility of using practically any character of coin-control mechanism.

5 A coin controlled slot 30 is shown, communicating with the coin-controlled mechanism, and it is obvious that the operator may insert a coin of whatever denomination has been found desirable within this slot in such 70 manner as to thereafter permit operation of the pump. The insertion of the coin, as in all coin-controlled mechanism, thereafter releases a latch or similar mechanism which permits then the operation of the manually 75 controlled plunger 31, the same having a control handle 32. Following the placement, by the motor vehicle operator, of the gasoline nozzle 16 within the motor vehicle tank, the operator then inserts a coin in the control 80 mechanism and thereafter forces the plunger 31 laterally and inwardly in a manner to initiate movement of the pump mechanism. The plunger 31 has a control member 33 carrying various members now to be described. 85

25 At its innermost end the control member has a cam face 34 disposed thereon in such manner that when moved inwardly the same will move under a vertically disposed valve stem 35 connected to the previously mentioned valve 17 controlling the flow of gasoline from the visible pump. Incidentally it might be stated that this valve stem is spring tensioned as at 36 to insure proper seating of the valve at all times and return of same 90 when released to a seated position.

Movement of the plunger inwardly obviously raises this valve, and as long as the operator holds the plunger in its innermost position, the valve 17 will be open and the 95 gasoline within the visible container will flow to the motor vehicle tank.

The operator may watch the visible tank until same has been exhausted, thereupon he releases the plunger 31 and same is withdrawn to a normal and outer position by 100 means of the coil spring 37 disposed between a depending bracket 38 and a similar bracket 39 on the control end 33 of the plunger 31.

50 A stationary bracket 40, fixedly secured to the pump standard or frame as at 41, provides a bearing support for the plunger and associated mechanism as well as for the valve stem 35.

55 The above described mechanism permits practical operation of the pump as respects withdrawal of the gasoline by the operator and even goes to the point of returning the plunger to a normal position preparatory to 105 a further operation by a subsequent customer. However, it does not accomplish the refilling of the visible tank, which is obviously necessary, and which must be accomplished automatically and prior to a subsequent insertion of a coin by a new customer.

The mechanism for accomplishing replenishing of the pump is as follows: Inasmuch as the ball float 24 was maintained in its normal upper position, which holds the lever controlled air valve 22 in a closed condition, any withdrawal of gasoline from the visible container would result in a downward movement of said ball float and a consequent opening of the air valve with a resulting automatic replenishing of the tank. This, of course, would defeat the purpose of the coin-controlled automatic feature, and in order to overcome this immediate replenishing of the pump upon withdrawal of gasoline therefrom, a support is provided for the ball float, 110 normally maintaining same in its upward position.

This support has been designated 42, the same being mounted on the float 24 and disposed at the upper end of stem 43 which is adjustably secured, as at 44, to a bell crank lever 45 pivoted at 46 to a bracket 47 disposed upon the bottom of the visible container. The bell crank lever has a slit connection 48 with a vertically disposed rod 49, projecting 115 through the bottom of the visible tank.

A simple leak-preventing mechanism or packing is shown at 50, such mechanism permitting a reciprocation of the rod 49 without leakage of gasoline from the bottom of the tank.

Movement of the rod 49 obviously controls the movement of the supporting member 42 for the ball float. An upward movement of the rod moves said support to the dotted line 120 position shown in Fig. 1, thereby releasing the ball float, and permitting same to descend in case gasoline has been withdrawn from the visible tank. This vertical rod 49 is adapted to be operated by a control member 51 pivoted at 52 on the plunger control portion 33 of the plunger 31.

We turn now to Figs. 7 and 8 for a more detailed description of this control member 51, which, as stated before, is pivoted to the control portion 33 of the plunger 31. It will be noted that there is an abutment 53 disposed at the left of this member 51, against which said member is normally retained by means of a very weak coil spring 54, secured at one end 55 to the member 51 and at its opposite end, as at 56, to a small upstanding lug 57 formed as an integral part of the control portion 33.

The manner of securing the member 51 with respect to the lower end of the rod 49 permits said member, upon inward movement of the plunger 31, to be moved beneath the lower end of the rod 49 without imparting upward movement thereto. This is obviously accomplished due to the very weak spring 54 which is overcome by the weight of the rod 49 and permits member 51 to pass thereunder upon inward movement of member 31. However, upon a return move- 125

ment of the plunger 31, the member 51 is supported at its rear side by means of the abutment 53 and due to the cam formation 58 upon its upper face, said member rides 5 against the lower end of the rod 49 and actually elevates said rod upon the return movement of the plunger. Mere release by the operator of this plunger is followed by an automatic return thereof, due to the expansion of 10 the coil spring 37. Thus, it is seen that the inward movement of the plunger in no way affects the rod 49 and hence through connected members the support 42 for the ball float so that during such inward movement said 15 ball float will not be affected and therefore, as long as the operator maintains the plunger in the inward position the gasoline within the visible tank will be permitted to drain out into the vehicle tank. However, upon 20 the exhaustion of gasoline in this tank and a resulting release of the control handle the return of the plunger to its normal position will result in the action of the member 51, or rather the cam face 58 thereof against the 25 lower end of rod 49 with a consequent elevation thereof, which elevation in turn moves the seat 47 to the dotted line position shown in Fig. 1, whereupon the ball float, unsupported by the gasoline, will drop to a lowered 30 position, with a resultant transmission of movement to the rod 25, thence to the adjustable bracket 28 and finally to the air pressure control valve 22.

This lowering of the ball float obviously 35 opens the air pressure valve and permits the air to create a pressure upon the auxiliary tank, which will result in the elevation of gasoline through the pipe 18 and finally into the visible tank. Inasmuch as the return of 40 the plunger has not only accomplished the release of the ball float and consequently the air pressure valve but also the release of the valve stem 35 and consequent seating of the valve 17, the gasoline that is projected into 45 the visible tank through the open end of the pipe 18 will be maintained therein and upon an accumulation of gasoline within the visible pump the ball float will again be raised to its normal position, as shown in Fig. 1 and 50 thus automatically close the air pressure valve 22 and therefore stop the flow of gasoline into the visible tank. As the ball float assumes its normal and elevated position, the seat 42 automatically slides thereunder and 55 again supports said ball float against downward movement until the plunger has again been moved inwardly, the gravity tank drained and the plunger released in a manner to actuate same in the manner heretofore described.

The raising of the ball float and the gradual closing of the air pressure valve obviously 60 stops the flow of gasoline, but to insure the maintenance of a predetermined volume of gasoline within the visible tank, in case such

closing of the valve should be even slightly retarded, there is provided the overflow pipe 19 which absolutely maintains a determined amount of gasoline within the container.

Referring now to Figs. 4 and 5 of the drawings, it will be noted that same are a slight modification of the mechanism heretofore described. Inasmuch as the entire pump has been described generally, it is thought sufficient to refer specifically only to those parts which differ in structure, inasmuch as the general principle of operation, as will be explained, is exactly the same.

In Figs. 4 and 5, means is provided for elevating the gasoline from the auxiliary tank 14 which is not exactly of the air pressure type, inasmuch as there is shown in this instance an electric motor 59 driving a pump 60 which in turn creates pressure upon the auxiliary tank 14 through the tube 61.

Upon energization of the electric motor and consequent movement of the pump 60 which has been shown but generally in the present instance and which pump it is understood can be varied as to construction to include practically any type of pump, pressure will be applied to the auxiliary tank with a consequent projection of gasoline through the pipe 62, the gasoline finally being forced into the visible tank from the open end of said pipe 62 in exactly the same manner as previously described with respect to pipe 18.

The overflow mechanism is exactly the same and it is not necessary to include even different numerals for the construction disclosed.

The only other difference in the pump lies in the fact that instead of utilizing the lever controlled air pressure valve 22, an ordinary switch mechanism, shown generally at 63, is used, the opening and closing thereof being controlled by vertical movement of the rod 25 and adjustable bracket member 28.

The movement of the rod 25, which has been described as controlling the projection of gasoline from the auxiliary tank into the visible container, is actuated in exactly the manner heretofore described, and in the present instance, when the ball float 24 is lowered and said rod 25 elevated, the switch 63 operates to close the electric circuit through the wires 64 to the electric motor, consequently causing said initial movement of said motor with a consequent movement of the pump 60 and application of pressure upon the auxiliary tank, which projects gasoline through the pipe 62 into the visible pump. Obviously, the resulting elevation of the ball float, due to the rising volume of gasoline within the visible container operates to depress the rod 25 and hence open the switch with the result that activity of the motor ceases, thus stopping the flow of gasoline to the visible container, the overflow member

125
130

operating to carry off any excess amount of gasoline and maintain a predetermined amount within the tank.

An ordinary fill pipe 65 is shown projecting from the upper side of the main gasoline tank 13 to a point well above the surface level, the same having a cover member 66 of conventional construction.

With respect to the operation of the coin controlled and automatically operating pump herein disclosed, it will be seen that the operator of a motor vehicle drives his car adjacent the pump, removes the cap from the gas tank of his vehicle, disposes 10 of the nozzle 16 of the pump within said container. He then places a coin of a given denomination within the slot 30 provided therefor in the coin controlled mechanism, thereafter manually grasping the portion 32 15 of the plunger 31 and forces same inwardly, with the result that valve 17 will be lifted and gasoline will flow from the visible tank into the tank of the car. This inward movement of the plunger causes member 51 to be forced beneath and to the opposite side of 20 the lower end of the rod 49.

When the operator finds the visible tank empty, he thereupon releases the plunger, which is immediately returned to its normal 30 position by means of spring 37, said plunger due to the control parts attached thereto upon its return movement operating to relieve tension upon valve 17, and permitting it to seat, and also in its return movement to actuate 35 the rod 49 in a manner to release the seat for the ball float, thereupon permitting said float to move downwardly in a manner to actuate the rod 25 and hence either open the air lever controlled pressure valve 22 or actuate 40 the switch 63 in such manner that pressure will be applied to the auxiliary tank and gasoline projected through either pipe 18, 21 or 62, into the visible tank.

As the visible tank gradually fills, the ball 45 float is elevated to its normal position and the seat 42 thereafter automatically moves thereunder and sustains same again in a normal and elevated position.

The raising of the ball float also accomplishes either a closing of the lever controlled 50 air valve 22 or the opening of the switch 63 to stop any further projection of gasoline, the overflow pipe acting to maintain a predetermined volume at all times in the visible 55 container. The coin controlled automatically operated pump is now in position to be used by the same operator if a larger amount of gasoline is required, or by another customer.

60 What we claim is:

1. In combination, a gasoline container having an outlet, valve means for opening and closing said outlet, coin controlled means for preventing operation of said opening 65 means except when a coin is deposited, means

for keeping gasoline in said tank at a predetermined level, means for rendering said third named means inoperative when said outlet is opened, and means operable when the valve is being closed for rendering said fourth named means inoperative whereby gasoline flows into said container. 70

2. In combination, a gasoline container having an outlet, valve means for opening and closing said outlet, coin controlled means for preventing operation of said opening means except when a coin is deposited, means for keeping gasoline in said tank at a predetermined level, means for rendering said third named means inoperative when said outlet is opened, and means operable when the valve is being closed for rendering said fourth named means inoperative whereby gasoline flows into said container, said fourth means returning to operative position when the container is filled to the predetermined level. 75

3. In combination, a gasoline container having an outlet normally closed, manually operable means for opening said outlet, coin controlled mechanism controlling the operation of said opening means, means for filling said container to a predetermined level, and means operable upon the closing of said outlet for controlling said filling means to 90 fill the container, whereby gasoline normally stands in said container. 95

4. In combination, a liquid container having an outlet, means for opening and closing said outlet, coin controlled means manually 100 movable to open said outlet, means for returning said manually movable means to its original position, means for filling said container with liquid to a predetermined level, means for rendering said filling means inoperative, means for closing said outlet upon the return of said manually movable means, means operable by the return of said manually movable means for rendering inoperative 105 said means for rendering the filling means inoperative. 110

In testimony whereof we have hereunto affixed our signatures.

JOHN C. HOLZ.
